THERAPEUTIC MACHINE

Faye De Ette Harrison, San Francisco, Calif.

Application December 5, 1951, Serial No. 17,620

Term of patent 14 years

(Cl. D83—1)

To all whom it may concern:

Be it known that I, Faye De Ette Harrison, a citizen of the United States, residing at 1256 Twelfth Avenue, San Francisco 16, State of California, have invented a new, original, and ornamental Design for a Therapeutic Machine, of which the following is a specification, reference being had to the accompanying drawing, forming a part hereof.

Fig. 1 is a perspective view of the machine in closed position.

Fig. 2 is a front elevational view of the machine in open position with its mirror in a position to provide access to its storage compartment.

Fig. 3 is a side elevational view of the machine in open position.

Fig. 4 is a perspective view of the machine in open position with its mirror in operative position.

The dominant features of my design reside in the portions shown in full lines of the drawing.

I claim:

The ornamental design for a therapeutic machine, substantially as shown.

FAYE DE ETTE HARRISON.
